UNITED STATES PATENT OFFICE

2,314,662

SAND ELIMINATOR

Nels Schedin, Milaca, Minn.; Frances Schedin administrator of said Nels Schedin, deceased

Application October 13, 1941, Serial No. 414,841

1 Claim. (Cl. 103—220)

My invention relates to pumps, particularly the suction pipe thereof, and has among its objects and advantages the provision of an improved water inlet device operating to eliminate agitation of the water at the well bottom so as to preclude the entry of sand and the like into the suction pipe.

In the accompanying drawing:

Figure 1 is an elevational view;

Figure 2 is a longitudinal sectional view; and

Figure 3 is a transverse sectional view along the line 3—3 of Figure 2.

In the embodiment selected for illustration, I make use of a tubular member 10 having a neck 12 provided with a threaded opening 14 for threaded connection with the bottom end of the suction pipe 16 of the pump (not shown). Member 10 is somewhat larger in diameter than the neck 12, and the neck is bent so as to bring the axis of the member 10 coincident with the axis of the pipe 16.

Neck 12 is narrowed at 18 so that one side of the member 10 projects beyond this wall of the neck substantially half its diameter, and this end of the projection is provided with an inlet opening 20. This opening is covered by a grill or strainer 22 arranged at an angle of about forty-five degrees to the axis of the member 10. A partition 24 is provided inside the member 10 to divide the member into passages 26 and 28. The partition terminates short of the closed end 30 of the member 10 so that water flowing downwardly in the passage 26 may reverse its flow as it passes underneath the partition 24 and upwardly into the suction pipe 16.

In operation, the invention prevents the entry

of sand into the suction pipe 16 in that the well water remains undisturbed at the bottom of the well. The inlet opening is located near the upper end of the member 10 and water entering the member flows downwardly so as to eliminate water disturbances close to the well bottom. Water is caused to flow downwardly as it enters the opening 20 which eliminates disturbances peculiar to upward movement of water close to the well bottom, as is peculiar to ordinary open-ended suction pipes. The grill 22 prevents large objects from being blown into the member 10.

Without further elaboration, the foregoing will so fully illustrate my invention, that others may, by applying current knowledge, readily adapt the same for use under various conditions of service.

I claim:

20 A sand eliminator for connection with the water inlet end of a pump suction pipe comprising a one piece tubular member closed at its bottom end and having a connection at its upper end for attachment to the pump suction pipe, said tubular member having a neck constricted at one side to project approximately half the diameter of said member laterally of said neck, said member being provided with a partition constituting a continuation of one side of said neck at the constricted side thereof to divide the member into a downwardly flowing passage and an upwardly flowing passage, the portion of the member projecting beyond said neck having an inlet opening in its upper end, and a grill extending across said inlet opening.
